UNITED STATES PATENT OFFICE.

JOHN S. L. RODRICK, OF WASHINGTON, DISTRICT OF COLUMBIA.

FURNACE.

SPECIFICATION forming part of Letters Patent No. 659,104, dated October 2, 1900.

Application filed June 1, 1900. Serial No. 18,715. (No model.)

To all whom it may concern:

Be it known that I, JOHN S. L. RODRICK, residing at Washington, in the District of Columbia, have invented a new and useful 5 Improvement in Furnaces, of which the following is a specification.

My invention is an improvement in furnaces having for an object to so construct the furnace as to insure the proper distribution 10 of its heat to the several flues and to enable the heat to be directed to a greater or less extent to any one or more of the flues, as may be desired.

In the drawings, Figure 1 is a perspective view of a furnace embodying my invention. 15 Fig. 2 is a vertical longitudinal section thereof. Fig. 3 is a cross-section on about line 3 3 of Fig. 2. Fig. 4 is a detail perspective view of the cap-plate. Fig. 5 is a detail perspective view of the combustion-chamber. Fig. 20 6 is a cross-sectional view on about line 6 6 of Fig. 2, and Fig. 7 is a detail perspective view of the check or smoke-deflector.

An important feature of my invention is 25 the provision of a series of upright superheating-chambers encircling the fire-pot and combustion-chamber and discharging at their upper ends into pipes or supplemental flues which may lead into the main heating-flues, 30 the purpose being to provide a large number of superheating-chambers, the heat from which may be directed into any desired one of the main heating-flues to increase the heat supplied to said main flue and also to induce 35 the circulation of the heat up through such flue.

In the construction shown the fire-pot A, with its grate B and the combustion-chamber C, may in general respects be of the ordinary 40 or other desired construction. Upon the outer side of the fire-pot A, I provide at desired intervals a number of upright flanges or plates A', extending to the upper end of the fire-pot. At such end the fire-pot is 45 joined by the lower end of the combustion-chamber C, and this combustion-chamber is provided on its outer side with the series of upright plates or flanges C', which meet at their lower ends the upper ends of the plates 50 A' of the fire-pot and coincide with and form extensions of the said plates A', as will be understood from the drawings. Upon the

combustion-chamber C is fitted the smoke-drum D, whose outer side is also provided with upright plates or flanges D', which coincide 55 with and form extensions of the plates C'. The plates or flanges D' extend to the top of the smoke-drum, and upon the latter is fitted a cap-plate E, which has an opening at F for the passage of the nipple G, which 60 connects with the offtake G'. This cap-plate E is also provided with openings and upwardly-projecting nipples E', with which the supplemental flues H or I connect. The nipples E' communicate with the superheating- 65 chambers formed between the flanges or plates A', C', and D', before described, and these chambers are inclosed by the jacket J, which encircles the fire-pot, combustion-chamber, and smoke-drum and is engaged at 70 its upper end by the depending flange E² on the cap-plate E. The casing K, with its top K', fits over the several parts and has connected with it the main heating-flues L, which may lead from the sides or top of the 75 casing, as may be desired, and receive the supplemental heating-flues H wherever necessity requires, it being well understood that in most houses heated by furnaces some flues naturally receive a large proportion of the 80 heat, while others receive practically none. By the use of the described construction the flue which receives but little heat may be supplied with a supplemental flue H, so the latter will aid the flue in which it is directed 85 both directly by the heat it conducts and indirectly by the added circulation which it induces in the said flue. Where a flue extends practically horizontal for some distance from the furnace, it may be desirable to extend the 90 supplemental flue to or nearly to the upward bend in the said heating-flue, as shown at the right in Fig. 2. It may also be desirable in some instances to conduct the heat from two or more of the superheating-chambers into 95 one of the main flues, and this may be accomplished by the construction of the supplemental flue shown at I in Fig. 4 and in which the flue is branched to connect with a plurality of the nipples E'. 100

The smoke-drum aids in the heating by extending the superheating-chambers and also by preventing the smoke from passing off too rapidly, to which end the drum has an inlet-

pipe at M in its bottom, which extends toward the rear of the combustion-chamber and is arranged to open into the smoke-drum at a point diametrically opposite the offtake G'. 5 Between the inlet and outlet I provide a check or deflector N, which may preferably consist, as shown, of a curved plate having upon its concave side a bail N', which may serve as a handle in adjusting the deflector and in the 10 use of the same as a scraper in clearing the bottom of the smoke-drum and may also serve as a support for the deflector when the same is applied for use, as shown in Fig. 2.

In the operation of my furnace, in addition to 15 the heat ascending in the usual way to the top, there to be drawn into the main flues as the caprices of the draft may direct, I secure a strong volume of heat ascending through separate superheating-chambers directly into each desired one of the main heating-flues and concentrate all the heat at the top of the furnace, so it can be properly supplied to the main heating-flues, as occasion may require. 20

My furnace can be readily cleaned of all 25 soot and dust, is simple in construction, and can be made at a small cost.

By securing a proper distribution of the heat and providing means by which to direct the heat to any desired point the use of the 30 furnace will result in a large saving of fuel.

Having thus described my invention, what I claim, and desire to secure by Letters Patent, is—

1. An improved furnace comprising the fire-pot, the combustion-chamber, upright plates 35 on the outer sides of same forming a series of longitudinal superheating-chambers, a smoke-drum upon the combustion-chamber and having on its outer side upright plates coinciding 40 with those on said combustion-chamber and forming continuations thereof, a cap on said smoke-drum and provided with nipples communicating with the superheating-chambers, the jacket around said fire-pot, combustion-

chamber and smoke-drum, the casing, the 45 heating-flues, and the superheating-flues communicating with the upper ends of the superheating-chambers and leading into the main heating-flues, substantially as set forth.

2. A furnace substantially as described 50 comprising the fire-pot and combustion-chamber, a series of upright, superheating-chambers extending around said fire-pot and combustion-chamber, a cap-plate at the upper end of said superheating-chambers and provided with openings communicating with said chambers, the casing and main heating-flues leading therefrom, and the superheating-flues 55 communicating with the superheating-chambers and discharging into the main heating-flues, substantially as set forth.

3. The combination in a furnace with the fire-pot, combustion-chamber and means forming a series of upright superheating-chambers around said parts, of the casing and main 65 heating-flues, and a cap-plate provided with openings communicating with the superheating-chambers, and the superheating-flues leading from said cap-plate to discharge into the main heating-flues, substantially as set forth. 70

4. In a furnace the combination of the combustion-chamber the smoke-chamber above the same and the inlet-pipe leading from the smoke-chamber into the combustion-chamber and deflected rearwardly within the latter, substantially as set forth. 75

5. In a furnace substantially as described, the combination of the combustion-chamber, the smoke-chamber and the combined scraper and deflector in the latter, said deflector being adjustable within the smoke-chamber and consisting of a plate and a bail or handle, substantially as set forth. 80
